FRANK D. CHAPMAN, OF BERLIN, WISCONSIN

SYSTEM OF AND MACHINE FOR GRADING PEAS

Application filed June 3, 1927. Serial No. 196,321.

This invention relates to improvements in system of and machine for grading peas and other edible articles or units of food.

In canning green peas the smaller sizes are considered more valuable and are sold for higher prices than the larger sizes and the prices received decrease as the size of the peas increase in size. It is, therefore, to the advantage of the canner in grading the peas to separate the peas into the different sizes or grades so that after grading the different sizes are completely separated from each other. The peas are separated by means of screens and in the event that the smaller size peas do not separate from the larger sizes, the peas are again run through a screening machine or regraded. This requires careful attention and considerable re-handling and is objectionable from many points of view.

It is one of the objects of the present invention to overcome the before mentioned objectionable features and provide a system of and machine for grading peas and other articles or units of food such as peaches, beets, etc., in which the rehandling and regrading will be eliminated and the food articles will be separated in the manner desired.

A further object of the invention is to provide a system of and machine for grading peas or other units in which all of the grading members are of the same form and size to permit easy interchanging, and also that longitudinally of the machine, the centers of all discharge chutes are equidistantly spaced apart so that the means for receiving the different grades of food articles may be likewise equidistantly spaced apart for inspection and handling.

A further object of the invention is to provide a system of and machine for grading peas and other articles of food in which some of the peas are automatically regraded or run over the same size screen more than once during their passage through the machine.

A further object of the invention is to provide a system of and machine for grading 50 peas in which the different grades or sizes

are separated and discharged from different portions of the machine.

A further object of the invention is to provide a system of and machine for grading 55 peas in which various combinations of sizes may be had by rearranging the screens in different positions with relation to each other.

A further object of the invention is to provide a system of and machine for grading 60 peas which is of simple construction and operation and is well adapted for the purpose described.

With the above and other objects in view the invention consists of the improved system of and machine for grading peas and its 65 parts and combinations as set forth in the claims, and all equivalents thereof.

In the accompanying drawings in which the same reference characters indicate the 70 same parts in all of the views:

Fig. 1 is a side view, parts in section, of the improved machine;

Fig. 2 is a transverse sectional view thereof taken on line 2—2 of Fig.; and

Fig. 3 is a front end view of the machine.

Referring to the drawings the numeral 8 indicates the main frame which is of rectangular form in cross section. The upper portion 9 of the frame inclines downwardly 80 rearwardly while supplemental frame members 10 are inclined downwardly, forwardly and are located intermediate the height of the frame. Four upper shafts 11 are journaled on the upper portion of the frame and 85 incline downwardly, rearwardly in the same plane as said frame part and have fast thereon in equidistantly spaced relation supporting rollers 12. The inner rollers are grooved while the outer end rollers are plain or un- 90 grooved. A line of open ended drums 13, 14, 15, 16, and 17 in endwise abutting relation are positioned between each pair of upper shafts 11 and are provided with flanged 95 annular end portions 18. The drums are all of the same length and the end flanges of adjacent drums abut each other and extend in pairs into the grooves of the rollers 12 while the outer end flanges of the opposite end drums extend on the outer sides of the 100

outer rollers 12. The rollers of each pair of shafts are closer together than the diameter of the annular flanged ends so that the line of drums are supported on said rollers in an inclined position. Other pairs of shafts 19 5 journaled in spaced relation on the supplemental frame 10 and extending longitudinally with relation to the frame have rollers 20 mounted fast thereon. Regarding drums 21 and 22 having annular end flanged portions 23 are supported on the rollers 20 in endwise spaced relation. The body portions 24 of the drums between the annular end parts are formed of perforated metal 15 and the diameters of the perforations of the upper drums increase $\frac{1}{2}$ of an inch in size from the front to the rear of the machine, the first drum 13 preferably having perforations $\frac{3}{2}$ of an inch in diameter and the 20 rear upper drum 17 having perforations of $\frac{1}{2}$ of an inch in diameter. Drum 13 having the smallest size openings will separate the No. 1 grade peas from the mixed mass, drum 14 the No. 2 grade, drum 15 the No. 3, drum 25 16 the No. 4 and drum 17 will separate the No. 5 from the No. 6 and larger peas which will be discharged from the rear end of the drum 17.

One shaft of each pair of the upper shafts 30 11 are rotated by a bevel gear connection 25 with an upper transverse driving shaft 26 having a belt wheels 27 mounted thereon. One of the lower shafts 19 of each pair also have a bevel gear driving connection 28 with a lower transverse shaft 29 and said lower shaft 29 is driven from the upper shaft 26 by a sprocket chain and wheel connection 30.

Hoppers 31 positioned in front of the forward ends of the drums 13 feed peas or other food articles into the said drums and the downward inclination and rotation of the drums causes the peas to travel through the drums and be separated by dropping 40 through the perforations which vary in size in the different drums until finally the No. 6 or largest size peas are discharged from the rear ends of the drums 17 and into the discharge spouts 32 located at said drum 45 ends. Hoppers 33 partly surrounding the lower portions of the drums 13 have discharge spouts 34 which extend to and are connected to the side portions of hoppers 35. Said hoppers 35 partly surround the lower 50 portions of the regrading drums 21 to receive No. 1 peas from the drums 21 and the hoppers 33 and discharge the same downwardly from the lower open ends 35' of said hoppers 35. Hoppers 36 partly surrounding the lower portions of drums 14 have 55 downwardly extending spouts 37 which enter the rearward ends of the regrading drums 21 to discharge No. 2 peas and any No. 1 peas which were not screened in the 60 drums 13, into the drums 21 for further separation.

aration from the No. 2. Discharge spouts 38 connected to loose drum ends 38' positioned at the forward ends of the drums 21 receive the No. 2 peas which have been regraded in the drum 21 and discharged therefrom. 70

Hoppers 39 extending around the lower portions of the drums 15 have discharge spouts 40 which extend to and are connected to the side portions of hoppers 41 which are positioned adjacent the lower portions of the drums 22. Said hoppers 41 receive No. 3 peas from the drums 15 and mix with the No. 3 peas from the drum 22. Other hoppers 42 extending around the lower portions of the drums 16 have discharge spouts 43 similar to the spouts 37 which extend into the rear ends of the regrading drums 22 and discharge thereinto No. 4 peas from the drums 16 for regrading. Spouts 44 connected to the ends 44' adjacent the forward ends of the drums 22 receive the regraded No. 3 peas therefrom for discharge through the said spouts. 80

Hoppers 45 extending around the lower half portions of drums 17 have spouts 46 for discharging the No. 5 peas received from the drums 17. 90

It is to be understood that while the machine shown is of a double type, one longitudinal half section may be used, or the regrading drums may be used in combination with any of the upper drums without departing from the spirit and scope of the invention. 95

It will be noted that longitudinally of the machine, all of the discharge spouts are equidistantly spaced from each other to provide for discharging the different grades of peas upon tables on endless belts (not shown) extending at right angles to the machine for inspection and final disposition. 100

It will also be understood that by making all of the drums of the same length and diameter and form, with the exception of the diameter of the perforations, that the drums are interchangeable to permit any relative arrangement of the different size screens, so that drums can be added or removed to change the capacity of the installation or the drums can be arranged to grade and regrade the edible units in any combination desired. It will also be understood that while the machine has been shown and described as a system for grading peas, the diameter of the perforations and position of the drums may be changed to grade other food products such as peaches, beets, etc., as desired. 110

From the foregoing description, it will be seen that the system of and machine for grading peas is of very simple construction, and is well adapted for the purpose described. 120

What I claim as my invention is:

1. The system of grading granular food, which comprises, passing the mixed food granules over a screen having relatively small openings, subsequently passing the oversize from the first screen over a second screen having openings of larger size than those of the first screen, passing the granulars delivered through the openings of the second screen through a third screen having openings of the same size as those of the first screen, and directly mixing the granules delivered through the first and third screens.
- 15 2. The system of grading granular food, which comprises, passing the mixed food granules over a revolving screen having relatively small openings while maintaining the granules in a state of constant agitation, subsequently passing the oversize from the first screen over a second revolving screen having openings of larger size than those of the first screen while likewise maintaining the granules in a state of constant
- 20 agitation, passing the granules delivered through the openings of the second screen over a third revolving screen having openings of the same size as those of the first screen while also maintaining the granules
- 25 in a state of constant agitation, and finally directly mixing the granules delivered through the first and third screens.

In testimony whereof, I affix my signature.

FRANK D. CHAPMAN.
